BUILDING CONSTRUCTION

Application filed March 7, 1929. Serial No. 345,074.

It is well known that vacuum insulation is many times more effective than other forms of insulation and this type has been used extensively in thermos bottles and other small articles of tubular form wherein the shape is such as to withstand the atmospheric pressure on opposite sides of the evacuated walls. The object of the present invention is to make this type of insulation available for wall construction and more particularly to provide such insulation in the form of flat slabs which may be set edge to edge in walls, thereby to form a vacuum insulated wall of any desired dimensions.

Wall construction of the type referred to involves a number of problems foreign to the art of vacuum bottles, chief of which are the following. Owing to the fact that the units must be flat instead of tubular the flat sides must be bridged at frequent intervals by braces adapted to counteract the atmospheric pressure on opposite sides of the slabs and thus prevent the flat sides from collapsing toward each other. The opposite sides of the slabs must be sealed throughout a long distance (along each of their four edges), instead of merely around a small neck as in the case of thermos bottles, thereby making it imperative to avoid seals of conducting material which would conduct a disproportionate amount of heat. The slabs must be constructed so that they may be transported and mounted in a wall without substantial danger of breakage and preferably so that if the vacuum walls are accidentally broken after the slabs have been incorporated in a wall the slabs do not collapse but still function as insulators comparable to the types now in use for refrigerator and building walls.

According to this invention the slabs preferably comprise two plates of glass, or other insulating material, sealed together around their peripheries with an evacuated space therebetween containing the aforesaid pressure counteracting bridges, and insulating material on the outside of each plate and surrounding the aforesaid peripheries. The glass plates may be integrally united either by fusing them together around their edges after being separately formed or by blowing

a slab with parallel sides. The layers of insulation on opposite sides of the glass body or core have margins projecting beyond the edges of the core and the spaces between the projecting margins may be filled with insulating material, preferably integral with the aforesaid layers. While this insulation housing for the glass core may be formed in various ways, as for example in the form of a continuous integral one piece covering of molded material such as ground cork, it is preferably formed in two sheets of cork, fiber board, asbestos board, or other insulating material, in which case the aforesaid margins may be made thicker so that they meet around the core, thereby avoiding the necessity of using separate filling material around the periphery of the core. In any case the layers of insulation on opposite sides of the core are united together to form a unitary structure. While the layers may be united through the medium of the core, as by adhesion to the core, they are preferably united directly together around the periphery of the core.

The invention is also preferably characterized in that the insulation housing for the glass core is of such nature that it may be nailed or screwed in place in the wall structure, thereby facilitating the process of erection and insuring permanency and rigidity of the resulting wall.

For the purpose of illustration typical embodiments of the invention are shown in the accompanying drawings, in which:

Fig. 1 is an elevation of a single unit;
Fig. 2 is a section on line 2-2 of Fig. 1; and

Fig. 3 is a partial section of a modification.

The particular embodiment shown in Figs. 1 and 2 comprises two glass plates 1 and 2, which are rectangular as shown in Fig. 1, and which are fused together around their peripheries as shown in Fig. 2. The opposing faces of these plates are spaced apart to provide a space 3 which is evacuated in any suitable way. The particular means for preventing the plates 1 and 2 from collapsing shown in Figs. 1 and 2 comprises protuberances 4 which project inwardly from each

plate and contact with the inner face of the opposite plate, these protuberances preferably being formed integrally with the glass plates. The opposing surfaces 5 of the glass plate are preferably silvered or otherwise rendered reflecting to minimize heat transference across the vacuum space.

As shown in Figs. 1 and 2 the aforesaid insulating casing comprises two sheets or layers 6 of cork or the like, each recessed to receive the glass core so that their marginal portions which project beyond the periphery of the core meet along the plane 7. The parts 6 may be secured together in any suitable way, as for example by cementing them together around their margins, or by cementing each sheet to the core, or in both ways.

The modification shown in Fig. 3 is similar to that illustrated in Figs. 1 and 2, except in the following particulars. The pressure counteracting means is in the form of columns 4', which may be formed of any suitable insulating material such as wood, and held in place in any suitable manner, as by cement. Instead of silvering the opposing faces of the glass plates 1' and 2', the space therebetween may be filled with finely divided material, either in powder or fibrous form, such as for example a mixture of silicon and comminuted carbon. The insulation covering in Fig. 3 is shown as a one-piece enclosure molded around the core of any suitable insulating material susceptible to a molding operation, as for example celotex.

I claim:

1. An insulation slab for use in building insulating walls, comprising two plates of insulating material sealed together around their peripheries with an evacuated space therebetween and a layer of insulating material on the outside of each plate, said layers being united beyond said peripheries to form a unitary structure which may readily be transported and attached in position in a wall.

2. An insulation slab for use in building insulating walls, comprising two plates of insulating material sealed together around their peripheries with an evacuated space therebetween, insulating bridges distributed throughout said evacuated space to counteract pressure on the outer faces of the plates, and a layer of insulating material on the outside of each plate, said layers being united beyond said peripheries to form a unitary structure which may readily be transported and attached in position in a wall.

3. An insulation slab for use in building insulating walls, comprising two glass plates integrally united around their peripheries with an evacuated space therebetween and a layer of insulating material on the outside of each plate, said layers being united beyond said peripheries to form a unitary struc-

ture which may readily be transported and attached in position in a wall.

4. An insulation slab for use in building insulation walls, comprising two plates of insulation sealed together around their peripheries with an evacuated space therebetween, and a layer of material on the outside of each plate extending beyond said peripheries, the space between said layers outside said peripheries being filled with insulating material, and said parts being secured together to form a unitary structure which may be safely transported and mounted in a wall.

5. An insulation slab for use in building insulation walls, comprising two plates of insulation sealed together around their peripheries with an evacuated space therebetween, and insulating material on the outside of each plate and surrounding said peripheries, the material on opposite sides being united beyond said peripheries to form a unitary structure which may be safely transported and mounted in position in a wall.

6. An insulation slab for use in building insulation walls, comprising two plates of glass integrally united around their peripheries with an evacuated space therebetween, a layer of insulation on the outside of each plate with margins projecting beyond said peripheries, and insulation material filling the space between said projecting margins, said insulation being united together to form a housing for the glass.

7. An insulation slab for use in building walls, comprising two plates of glass integrally united around their peripheries with an evacuated space therebetween, a layer of insulation on the outside of each plate with margins projecting beyond said peripheries, and insulation material filling the space between said projecting margins, said insulation material being integral with said layer insulation and all of said insulation being united together to form a housing for the glass.

Signed by me at Boston, Mass., this 13th day of November, 1928.

DANIEL F. COMSTOCK.
